UNITED STATES PATENT OFFICE.

MINERVA J. STEPHENSON, OF SEWARD, NEBRASKA.

WATER CUT-OFF.

992,614.

Specification of Letters Patent.

Patented May 16, 1911.

Application filed May 12, 1910. Serial No. 560,931.

To all whom it may concern:

Be it known that I, MINERVA J. STEPHENSON, a citizen of the United States, residing at Seward, in the county of Seward, State 5 of Nebraska, have invented certain new and useful Improvements in Water Cut-Offs; and I do hereby declare the following to be a full, clear, and exact description of the invention, such as will enable others skilled in 10 the art to which it appertains to make and use the same.

This invention relates to water cut-offs of that general class designed to permit of the escape of a predetermined amount of water 15 through a conductor pipe from the eaves, and to automatically direct the stream into the cistern or other container after the first or polluted portion has escaped.

The object of this invention is to provide 20 a simple and less expensive device of this character than hitherto obtainable and to so construct this device that the deflecting mechanism will be entirely concealed from view.

25 With the above and other objects in view, the invention consists of the novel details of construction and combination of parts hereinafter fully described and claimed, it being understood that various modifications may 30 be made in the minor details of construction within the scope of the appended claims.

In the accompanying drawings forming part of this specification: Figure 1 is a longitudinal sectional view of the device showing 35 the deflecting mechanism in position for permitting the escape of the first portion of the stream. Fig. 2 is a longitudinal sectional view through the device showing the deflecting mechanism in position for directing 40 the stream to the container. Fig. 3 is a longitudinal sectional view taken on the line 3—3, Fig. 1. Fig. 4 is a rear perspective view of the gate.

Referring now to the drawings, the reference 45 character 11 designates the entering pipe, the upper end of which is fitted to the conductor pipe leading from the eaves, and this entering pipe is provided at its lower end with a pair of inclined branches 12 and 50 13 adapted to direct the stream from the eaves to the cistern and upon the ground respectively. The pipe 12 leading to the cistern will be hereinafter referred to as the cistern pipe and the pipe 13 leading to the 55 ground will be hereinafter referred to as the escape pipe. The escape pipe as will be

noted has its open end lying substantially in the horizontal plane of the bottom edge of the delivery pipe, this construction being preferably in order to mount the gate actuating mechanism which will be now described. 60

Extending transversely across the open end of the discharge pipe is a worm 14, one end of this worm being provided with a reduced neck 15 which extends through the 65 wall of the exhaust pipe, and is then provided with a rivet head 16 which retains the worm in position. The free end of the worm terminates a short distance from the opposite wall of the discharge pipe and is 70 disposed a slight distance above the horizontal plane of the open end of this pipe. Mounted upon the worm is a water wheel 17 having a tubular hub 18 which is threaded internally and travels along the worm. Arranged upon the hub are plate like blades 19, these blades being preferably four or six 75 in number, although any desired number may be employed, and each blade is spaced from the hub by a pair of spaced spokes 20. 80 It will be observed that the water wheel is free to rotate upon the shaft and when rotated in one direction will advance along the worm toward the free end of the latter which movement as will hereinafter appear is utilized 85 in opening a gate 21.

The gate 21 comprises a pair of curvilinear sections 22 and 23, these sections being hingedly connected together at their meeting straight edges in any desired manner, the preferred construction being to form adjacent each corner of one of the sections a pair of hinge lugs 24 and to form on the corresponding corner of the mating section a hinge lug 25 which fits between the 95 hinge lugs 24 and is connected to the latter by means of an ordinary pintle 26. Thus the hinges are considerably spaced apart so that but an inconsequential opening will be left 100 between the sections whereby leakage therebetween will be very slight.

The above described gate is hingedly connected at one end to the lower wall of the cistern pipe, this connection being effected by means of an ordinary butt hinge 27, one 105 leg of which is fixed to the gate and the opposite leg of which is fixed to the side wall of the pipe. This hinge is preferably so mounted as to hold the lower section 22 of the gate in the position shown in Fig. 1 110 when the gate is in closed position, the section 22 in this position being inclined at an

angle approximately 30 degrees to the bottom wall of the cistern pipe and the top flat edge of this plate being disposed in horizontal alinement with the outer edges of 5 the paddle wheels 19. When the lower section is in the position above described, the upper section 22 will be inclined oppositely to the lower section and will rest with its upper edges against the side wall of the entering pipe 10. When in this position of 10 the parts, the stream flowing from the eaves will be directed through the entering pipe and discharge pipe since the mouth of the cistern pipe is sealed by the gate. Thus 15 water when flowing through the discharge pipe actuates the water wheel.

For utilizing the advancing movement of the water wheel, an arcuate resilient finger 28 is fixed to the forward outer corner of one 20 of the blades, the free end of this finger terminating approximately in alinement with the inner longitudinal edge of the water wheel. Fixed on the reverse face of the gate is an arcuate plate 29, this plate having 25 upon one of its longitudinal edges a flange 30 through which and the lower section of the gate, bolts or similar connectors 31 are passed to rigidly secure the parts together. This plate is disposed to arch over the hinge- 30 edly connected straight edges of the gate sections and when the gate is in closed position is disposed in horizontal alinement with the arcuate finger carried by the water wheel. As the water wheel advances upon the 35 worm, the arcuate finger will be advanced into engagement with the arcuate plate and a further advancing movement of the water wheel serves to rock the sections of the gate open similar to a toggle lever, this opening 40 movement of the sections causing the upper section to rock into engagement with the opposite wall of the entering pipe and permit of the stream entering the cistern pipe. The advantage of employing an arcuate 45 plate 31 is to minimize the jar on the gate as the water wheel advances into engagement therewith. For guiding the upper section 22 of the gate in its rocking movement, I provide a pair of guide pins 32 and 33 50 which project inwardly from one of the side walls of the entering pipe and engage the opposite side faces of the upper section of the gate. It will now be seen that when the water wheel advances into engagement with 55 the gate that the upper section of the gate will be accurately rocked to its open position, the stream of water operating to facili-

tate this opening movement when the gate has advanced slightly beyond the perpendicular in its opening movement.

For causing the stream of water to rotate the water wheel in the proper direction, a semicircular plate 34 is mounted within the entering pipe. The plate is provided upon its straight edge with a flange 35 through 60 which and the side wall of the entering pipe bolts, rivets or similar connectors 36 are passed to effectively secure the parts together. The plate is inclined downwardly from the side wall toward the axial diameter of the stand pipe so that the stream will be directed toward the side of the stand pipe opposite that side upon which the plate is fixed and will strike against the water wheel disposed adjacent said side, thus operating 65 to rotate the water wheel in the desired direction.

A hinged door 37 closes an opening 38 formed in one side of the entering pipe above the water wheel and permits the 80 water wheel being rotated back to its initial position after each storm so that the gate may be manually set in operative or open position.

It will be noted that a device constructed 85 as above described will be simple and inexpensive and further will have all its deflecting mechanism concealed from view.

What is claimed is:—

1. A water cut off comprising an inlet 90 pipe and branched discharge pipes connected therewith, a toggle gate normally directing the flow into one of said discharge pipes, and a water wheel adapted to engage and cause said toggle gate to move so as to direct the flow into the mating discharge pipe.

2. A water cut off comprising an inlet and a plurality of outlet pipes, a toggle gate adapted to be manually moved into a closed position whereby to direct the flow from the 100 inlet pipe into one of the outlet pipes, a water wheel operating to move the gate to open position whereby to direct the flow into the mating discharge pipe, and a baffle arranged in the inlet pipe and directing the 105 flow so as to cause the water wheel to rotate in an operative direction.

In testimony whereof, I affix my signature, in presence of two witnesses.

MINERVA J. STEPHENSON.
